DESIGN FOR A DECORATIVE LIGHT ORNAMENT

Sidney K. Lane, New York, N. Y., assignor to
Noma Electric Corporation, New York, N. Y., a
corporation of New York

Application October 1, 1948, Serial No. 148,914

Term of patent 14 years

(Cl. D48—20)

To all whom it may concern:

Be it known that I, Sidney K. Lane, a citizen of the United States, residing at New York, Bronx County, and State of New York, have invented a new, original, and ornamental Design for a Decorative Light Ornament, of which the following is a specification, reference being had to the accompanying drawing, forming part thereof.

Fig. 1 is a top plan view of a decorative light ornament embodying my new design;

Fig. 2 is a side elevational view of the same, and
Fig. 3 is a bottom end view thereof.

The dominant features of my new design reside in the portions shown in full lines.

I claim:

The ornamental design for a decorative light ornament, substantially as shown and described.

SIDNEY K. LANE.
